DRY CLEANING WASHER

Albert F. Widigen, Davenport, Iowa, assignor to
American Machine and Metals, Inc., New York,
N. Y., a corporation of Delaware

Application June 8, 1950, Serial No. 166,859

23 Claims. (Cl. 169—2)

1 This invention relates to dry-cleaning washers, tumblers, and similar machines, and more particularly to the safety devices with which such machines have to be equipped on account of the easily inflammable character of the cleaning fluids used, such as gasoline, naphtha, or the like.

It is customary to provide dry-cleaning machines with a closing mechanism for the shell door, including a fusible link and a spring, which mechanism, in the event of an explosion occurring in the washer, causes the shell door, if it happens to be open at the time of the explosion, to fall shut. It is also customary to provide in the rear part of the shell a normally closed explosion relief opening to allow the force of an explosion to expend itself into the atmosphere in a direction away from the operator. It has further been proposed to connect the washer with a supply of fire extinguishing fluid, such as steam or an inert gas, such as carbon dioxide and to control the admission of this fluid to the washer by a fusible member which will melt when a fire occurs in the washer.

The hitherto known safety devices suffer from certain drawbacks, among which are, in some constructions, the control of only part of the dangers accompanying an explosion in the dry-cleaning machine, the failure to operate safely in consequence of an explosion when the shell door is open in other constructions, and the danger to the operator of being hit by the shell door suddenly coming down to its closed position in consequence of an explosion in the machine in still other constructions.

It is an object of this invention to provide a dry-cleaning machine, such as a dry-cleaning washer, with a safety device which is highly efficient and free from the just mentioned shortcomings of the prior art safety devices.

A further object of the invention is to provide a dry-cleaning machine having a door at the front of the shell and an explosion relief opening in the rear of the shell normally closed by a movable cover, which cover is biased so that upon the occurrence of an explosion in the machine it will move into such an open position as to bear against the shell door causing the latter, if open, to start its closing movement.

A further object of the invention is to provide a dry-cleaning machine having means for counter-balancing to a desired extent the shell door, so that this door, after it has been caused to start its closing movement, will not come down to its closing position under the unhampered action of its own weight, but at an appreciably reduced speed.

2 Another object of the invention is to provide a dry-cleaning machine wherein the movable cover for the explosion relief opening forms part of a box communicating with the interior of the shell through an aperture which is closeable by a normally partly open closure that will open further upon the occurrence of an explosion in the shell, and in this event will operate opening means for said movable cover.

5 10 A further object of the invention is to provide a dry-cleaning machine wherein a common breakable, e. g. fusible, member controls spring-biased means for opening the cover of an explosion relief opening, as well as spring biased means for admitting a fire extinguishing fluid into the shell, both said means being equally effective whether the shell door is open or closed at the time of the explosion.

15 20 Still a further object of the invention is to provide a dry-cleaning machine having the above mentioned normally partly open closure for an aperture in the rear part of the shell and a fusible member for controlling the opening means for admitting the fire extinguishing fluid, wherein said normally partly open closure is arranged so as to direct the blast of an explosion occurring in the shell towards said fusible member.

25 30 Other objects and advantages of the invention will appear as the description proceeds, reference being had to the accompanying drawings which show, by way of example, one embodiment of the invention and in which:

35 Fig. 1 is a side elevation, partly in section, of a dry-cleaning washer equipped with the invention, a portion of the shell being broken away;

40 Fig. 2 shows, on a much larger scale than Fig. 1, a top plan view of a box attached to the rear of the shell, the box cover being removed for greater clarity;

Fig. 3 is a vertical section along line 3—3 in Fig. 2; and

Fig. 4 is a vertical section along the line 4—4 in Fig. 2 with part of tube 46 and member 44 broken away.

Referring now to the drawings: Secured to a base 10, such as by means of bolts 11, is the stationary shell 12 of a dry-cleaning washer. In the front of the shell 12 there is provided an opening 13, which is closeable by a shell door 14 hinged on a shaft 15 supported by the shell 12. Rotatable within the shell 12 is a cylinder 16, which at each end is journaled by means of a trunnion 17 in a bearing 18 carried by the base 10. The cylinder 16 is equipped with a door (not shown) permitting, when open, the insertion into,

or the removal from, the cylinder 16 of the work to be dry-cleaned.

Behind the hinge 15, which carries the shell 12, there is attached to the outside of the door 14, there is attached to the outside of the shell 12 an upwardly extending box or stack denoted generally as 20. The box 20 has a front wall 21, a back wall 22, and two side walls 23 and 24. Hinged to the front wall 21 of the box 20, so as to be turnable about an axis 28, is a lid 27 which is closed during normal operations of the machine, but serves as an explosion-relief opening for the washer in case of an explosion therein, as will be described later. The lid 27 has attached to its top a frame generally denoted as 29, which comprises two horizontal legs 30 welded to the top of the lid 27 and terminating each in a curled-up part 31, two vertical legs 32 and a cross bar 33 connecting the two vertical legs 32.

The bottom of the box 20 is formed by a portion 25 of the wall of the shell 12 and this bottom has an aperture 26 by means of which the box 20 ordinarily communicates with the interior of the shell 12. The aperture 26 can be closed by a closure 34 which is turnably mounted on a pivot 35 carried by a stationary part of the box 20, such as by the bottom 25 or by the side wall 24 of this box. The closure 34 has a rearward extension 36, by means of which the closure 34 can be held in the partly opened position shown in Fig. 3 when a surface cam 37 is in the position shown, in which it prevents the extension 36 and the closure 34 connected therewith, from turning in counter-clockwise direction. This position of the cam 37 being its normal position, the closure 34 is normally ajar with the end 16 of the closure 34 at the distance shown in Fig. 3 from the edge 11 of the aperture 26.

Positioned closely above the partly opened closure 34 is a bar 39, which forms part of an opening device for the lid 27 of the box 20. The bar 39 comprises, as may be seen best from Fig. 4, two U-shaped pieces 40 and 41, each having secured to one of its legs one end of a bar 42. The other end 43 of the U-shaped rod 40 has an extension 56 which extends perpendicularly to the U-piece 40 and is welded or otherwise rigidly secured to a member 44 which carries the cam surface 37 and rides loosely on a stud 45 extending through a tube 46 passing through a hole in the side wall 24 of the box 20. The inner end of the stud 45 carries a collar 47 through which a hole 48 is drilled. A similar hole 49 is drilled through the member 44 and the two holes 48, 49 accommodate the two ends of a coil spring 50 which surrounds a portion of the length of the stud 45. The outer end 51 of the stud 45 is reduced in diameter so as to form a shoulder 52, and it carries a thread at its outside so that a nut 53 having a corresponding inner thread can be screwed thereon. The nut 53, when tightened, presses against a washer 54 which, in turn, rests against the shoulder 52. Since the member 44 is ordinarily held by the bar 39 against turning on the stud 45, tightening of the nut 53, after it has come to bear upon the washer 54, will cause a rotation of the stud 45 relative to the member 44 and thereby a winding up of the spring 50 held at one end by that member 44. Set screws 55 are provided for locking the stud 45 in fixed relation to the tube 46, which set screws are tightened after the spring 50 has been wound up to the desired degree.

In similar manner as the outer end 56 of the U-shaped piece 40 is rigidly secured to the member 44 on the stud 45 extending through the one

side wall 24 of the box 20, the outer end 56' of the other U-shaped piece 41 is secured to a member 44' on a stud 45' which extends through the other side wall 23 of the box 20. Parts denoted in the drawing by the reference numerals 46', 47', 50', 51', 53', 54', 55', and 56' are provided for cooperation with the stud 45' in the same manner as the corresponding parts 46, 47, 50, 51, 53, 54, 55 and 56 are coordinated to the stud 45. It is to be noted, however, that the thread on the reduced end 51' of the stud 45' is opposite to the thread on the end 51 of the stud 45 so that for tightening the two nuts 53 and 53', they have to be turned in opposite directions, their inner threads being for that purpose also opposite to each other. The bar 42 extending between the two U-shaped pieces 40 and 41 carries a pin 57 to which one end of a fusible link 58 is attached. The other end of the fusible link 58 is attached to a pin 59 carried by a substantially U-shaped piece 60, which is pivoted at 61 on a lug 62 attached to a cylinder 63, in which a piston 64 having a piston rod 65 is slidably mounted. The piece 60 has a downwardly projecting part 74 which, when the fusible link 58 is intact, is situated in the path of the piston 64. Thereby the part 74 prevents a forward movement of the piston 64 under the action of a compressed spring 68 inserted between the back of the piston 64 and a rear cover 66 for the cylinder 63 formed by one end of a U-shaped bracket 67, which is fastened to the back wall 22 of the box 20 by means of rivets 75, or the like. The other end 69 of the bracket 67 supports a fluid valve 70 which forms part of a system for the supply of fire extinguishing fluid into the washer in case of an explosion or a fire occurring therein. The fire extinguishing fluid, which may be steam or a gas or a suitable liquid, enters the valve 70 by a pipe 71 and passes from the valve, if the latter is open, into the interior of the shell 12 through a pipe 72. The valve 70 has a stem 73 which is arranged coaxially with the piston 64 and at a distance therefrom when this piston 64 is held against the action of the spring 68 in the position shown in Figs. 2 and 3 by the projection 74 of the piece 60. This is the case while the fusible link 58 is intact. When this link 58 is ruptured under the now released action of the spring 68, the piston 64 first pushes the projection 74 out of its way and then hits the stem 73 whereby the valve 70 is opened.

While the springs 50 and 50', through the intermediary of the bar 42 to which one end of each of these springs is connected, exert an upward thrust upon the link 58, the spring 68 in the cylinder 63, through the intermediary of the piece 60, exerts a downward pull on the link 58. The link 58 is made strong enough to withstand the resultant of the forces just named, but it will break, even without fusing, if a substantial force is added to that resultant. Such an additional force becomes effective upon the link 58 if an explosion occurs within the shell leading to a sudden increase in pressure, which will force the normally partly open closure 34 to open wider. In so doing, the closure 34 strikes with great force against the under side of the bar 39, and the link 58 is not strong enough to withstand the upward pull thereby exerted upon its upper end. The link 58 breaks and thereby allows a number of actions to take place:

(1) The springs 50 and 50' are set free to turn the bar 39 in clockwise direction about the shafts 75 45, 45', pushing by means of the U-shaped pieces

40 and 41 the lid 27 of the box 20 wide open about its hinge 28.

(2) Moving with the lid 27 is the frame 29 against whose curled-up parts 31 the shell door 14, if open, is leaning during normal operation of the machine. If the shell door 14 happens to be open at the time of an explosion, the curled-up parts 31, moving with the lid 27, about pivot 28 will immediately start the door 14 towards its closing position. Soon after this movement has started, the cross bar 33 of the frame 29, which turns about the axis 28 at a faster rate than the parts 31, reaches the already moving shell door 14, imparting to the latter a strong impact which will secure the movement of the shell door to a point from which this door will continue its movement toward the closed position under the action of gravity. To control this action of gravity so that the door 14 will come down to its closing position at such a moderate speed that even if the operator of the machine should just be reaching into the cylinder thereof when the shell door comes down, the door will neither injure the operator nor prevent him from withdrawing from the machine. Such a moderate closing speed of the shell door is secured by counter-balancing means comprising on either one end or on both ends of the shaft 15 a disk 76. To the rim of the disk 76 one end of a flexible steel band 77 is secured. The other end of the band 77 is secured to the rim of a roller 78 mounted on a pivot 79, which is carried by a bracket 80 attached to the frame 10. The roller 78 carries a bent lever 81 on which there is adjustably mounted a weight 82 held in its adjusted position by a set screw 83. When the shell door 14 is closed, the lever 81 extends from its pivot 79 upwardly at an angle α to the horizontal direction and by proper selection of the angle α and the position of the weight 82 on the lever 81, the counter-balancing effect of the weight 82 may be chosen so that the door 14, after having been started on its closing movement, will not accumulate speed on its way down as it would if left to the unhampered action of its own weight. Instead, since the torque of the weight 82 about the pivot 79 is opposed to the torque of the door 14 about the shaft 15, the door 14 will come down at a speed only which may be equal to, or less than, the speed at which the door was started by the impact of the frame 29 hitting the back of that door. In this manner, should the operator have his head under the door when the latter comes down, he will suffer no injury by being forcibly hit in the back of the neck as might be the case if the counter-balancing means just described were absent.

(3) The pre-stressed spring 68 bearing upon the back of the piston 64 in the cylinder 63, no longer opposed by the link 58, turns the piece 60 about its pivot 61 until the extension 74 of the piece 60 is out of the path of the piston 64, wherupon this piston, still under the action of the spring 68, moves forwardly so as to hit the stem 73 of the valve 70, admitting thereby fire extinguishing fluid through the pipe 72 into the shell 12. The operation of the valve 70 is independent of whether the shell door 14 is open or closed at the time the link 58 is ruptured.

(4) Together with the bar 39, the member 44 having the cam surface 37 is turned about the axis of the stud 45 so as to move the cam surface 37 out of the path of the extension 36 of the closure 34. This permits the closure 34, as soon as the force of the explosion has spent itself, to fall

shut so that the interior of the shell becomes separated from the atmosphere and the fire within the shell is smothered rapidly by the fire extinguishing fluid as well as by the lack of sufficient air to support combustion.

It will be noted from Fig. 3 that the closure 34 is arranged so as to direct any hot gases coming from the shell through the aperture 26 towards the fusible link 58. Thus, if there occurs an explosion or fire in the washer, the heat therefrom will immediately reach the fusible link 58 and melt the same, with the results already described in connection with a mechanical breaking of the link 58.

After the fire in the shell has been put out, the shell door 14 is opened to permit any gaseous residues to escape, the broken fusible link 58 is replaced by a new one and the parts controlled by this link, including the springs 50, 50' and 20 68, are pre-stressed for the next operation.

While I have shown in the drawing one particular embodiment of the invention, I desire it to be understood that this embodiment has been given by way of example only, since various 25 modifications and changes in the construction and arrangement of the parts of the illustrated machine may be made without departing from the spirit of the invention or the scope of the appended claims.

What I claim is:

1. In a dry-cleaning washer, in combination, 35 a shell, an opening in the front side of said shell, a shell door mounted on a hinge at the top of said opening and adapted to close the latter, an explosion relief opening behind said hinge, a normally closed movable cover for said relief opening, opening means for said cover including at least one element biased for causing said opening means to move said movable cover into such 40 an open position as to bear against said shell door if the latter is open, a member adapted to break in consequence of an explosion within said shell, said breakable member being so connected to said opening means as to restrain, 45 while intact, said opening means from responding to the bias of said biased element or elements and, upon its rupture, to release said opening means for opening said movable cover under the action of said biased element or elements 50 into said position in which it bears against the open shell door, causing thereby said shell door to close.

2. In a dry-cleaning washer, in combination, 55 a shell, an opening in the front side of said shell, a shell door mounted on a hinge at the top of said opening and adapted to close the latter, an explosion relief opening behind said hinge, a normally closed movable cover for said relief opening, opening means for said cover including 60 at least one prestressed spring adapted to cause said opening means to move said movable cover into such an open position as to bear against said shell door if the latter is open, a fusible link adapted to break in consequence of an explosion within said shell so connected to said opening means as to restrain, while intact, said prestressed spring or springs from acting upon said opening means and, upon its rupture, to release said spring or springs for action upon said opening means to open said movable cover into said position in which it bears against the open shell door, causing thereby said shell door to close.

3. A dry-cleaning washer which will instantaneously vent an explosion therein without blow-

ing the loading door open against the operator, having in combination, a shell, an opening in the front side of said shell for the loading door, a shell door mounted on a hinge at the top of said opening and adapted to be closed during the operation of the washer, a box attached to the outside of said shell behind said hinge and communicating with the interior of said shell through an aperture therein, a closure for said aperture in said box which is normally latched partly open and adapted to be opened further by the force of the explosion within said shell, an opening in one wall of said box to the atmosphere, a normally closed cover for said opening, a device providing the energy for moving said cover to a position where the opening from the box to the atmosphere is unobstructed, means normally restraining said device from acting which are adapted to be ruptured by the movement of the closure of said aperture beyond its initial partly-open position.

4. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a normally partly open closure for said aperture adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move said cover into such an open position as to bear against said shell door if the same is open, a member adapted to break in consequence of an explosion within said shell so connected to said opening means as to restrain, while intact, said opening means from responding to the bias of said biased element or elements and, upon its rupture, to release said opening means for opening said movable cover under the action of said biased element or elements, and at least one extension on said cover adapted to engage in said open position of said cover said shell door for initiating the movement of the latter towards its closing position.

5. In a dry-cleansing washer, in combination, a shell, an opening in the front side of said shell, a shell door mounted on a hinge at the top of said opening and adapted to close the latter, an explosion relief opening behind said hinge, a normally closed movable cover for said relief opening, opening means for said cover including at least one element biased for causing said opening means to move said movable cover into such an open position as to bear against said shell door if the latter is open, a member adapted to break in consequence of an explosion within said shell, said breakable member being so connected to said opening means as to restrain, while intact, said opening means from responding to the bias of said biased element or elements and, upon its rupture, to release said opening means for opening said movable cover under the action of said biased element or elements into said position in which it bears against the open shell door, causing thereby said shell door to close, and counterbalancing means connected to said shell door adapted to reduce the speed of the closing movement of said shell door below the speed at which this door, upon its closing movement having been initiated by said movable cover for said relief opening, would come down to its closing position under the unhampered action of its own weight.

6. In a dry-cleaning washer, in combination, a shell, an opening in the front side of said shell, a shell door mounted on a hinge at the top of said opening and adapted to close the latter, an explosion relief opening behind said hinge, a normally closed movable cover for said relief opening, opening means for said cover including at least one element biased for causing said opening means to move said movable cover into such an open position as to bear against said shell door if the latter is open, a member adapted to break in consequence of an explosion within said shell, said breakable member being so connected to said opening means as to restrain, while intact, said opening means from responding to the bias of said biased element or elements and, upon its

rupture, to release said opening means for opening said movable cover under the action of said biased element or elements into said position in which it bears against the open shell door, causing thereby said shell door to close, and counterbalancing means for said shell door including a weight carried by a lever turnable about a pivot and extending from said pivot upwardly at an angle to the horizontal direction and a flexible member connecting the pivotal end of said lever to the hinged end of said shell door, so that said weight participates in the movement of said shell door and reduces the speed of the closing movement of said shell door below the speed at which this door, upon its closing movement having been initiated by said movable cover for said relief opening, would come down to its closing position under the unhampered action of its own weight.

7. In a dry-cleaning washer, in combination, a shell, an opening in the front side of said shell, a shell door mounted on a hinge at the top of said opening and adapted to close the latter, an explosion relief opening behind said hinge, a normally closed movable cover for said relief opening, opening means for said cover including at least one prestressed spring adapted to cause said opening means to move said movable cover into such an open position as to bear against said shell door if the latter is open, a fusible link adapted to break in consequence of an explosion within said shell so connected to said opening means as to restrain, while intact, said prestressed spring or springs from acting upon said opening means and, upon its rupture, to release said spring or springs for action upon said opening means to open said movable cover into said position in which it bears against the open shell door, causing thereby said shell door to close, and counterbalancing means connected to said shell door adapted to reduce the speed of the closing movement of said shell door below the speed at which this door, upon its closing movement having been initiated by said movable cover for said relief opening, would come down to its closing position under the unhampered action of its own weight.

8. In a dry-cleaning washer, in combination, a shell, an opening in the front side of said shell, a shell door mounted on a hinge at the top of said opening and adapted to close the latter, an explosion relief opening behind said hinge, a normally closed movable cover for said relief opening, opening means for said cover including at

least one prestressed spring adapted to cause said opening means to move said movable cover into such an open position as to bear against said shell door if the latter is open, a fusible link adapted to break in consequence of an explosion within said shell so connected to said opening means as to restrain, while intact, said prestressed spring or springs from acting upon said opening means and, upon its rupture, to release said spring or springs for action upon said opening means to open said movable cover into said position in which it bears against the open shell door, causing thereby said shell door to close, and counterbalancing means for said shell door including a weight carried by a lever turnable about a pivot and extending from said pivot upwardly at an angle to the horizontal direction and a flexible member connecting the pivotal end of said lever to the hinged end of said shell door so that said weight participates in the movement of said shell door and reduces the speed of the closing movement of said shell door below the speed at which this door, upon its closing movement having been initiated by said movable cover for said relief opening, would come down to its closing position under the unhampered action of its own weight.

9. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a normally partly open closure for said aperture adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move said cover into such an open position as to bear against said shell door if the same is open for initiating the closing thereof, and a breakable member so connected to said opening means as to restrain, while intact, said opening means from responding to the bias of said biased element or elements and, upon its rupture, to release said opening means for opening said movable cover under the action of said biased element or elements, said normally partly open closure being pivotally mounted closely underneath said opening means for said cover so that in consequence of an explosion within said shell said closure will strike against said opening means.

10. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a normally partly open closure for said aperture adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move

said cover into such an open position as to bear against said shell door if the same is open, and a fusible link so connected to said opening means as to restrain, while intact, said opening means from responding to the bias of said biased element or elements and, upon its rupture, to release said opening means for opening said movable cover under the action of said biased element or elements, said normally partly open closure being arranged so as to direct the blast of an explosion occurring in said shell towards said fusible link.

11. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a normally partly open closure for said aperture adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move said cover into such an open position as to bear against said shell door if the same is open, and a fusible link so connected to said opening means as to restrain, while intact, said opening means from responding to the bias of said biased element or elements and, upon its rupture, to release said opening means for opening said movable cover under the action of said biased element or elements, said normally partly open closure being pivotally mounted closely underneath said opening means for said cover and in such position as to direct the blast of an explosion occurring in said shell towards said fusible link.

12. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a normally partly open closure for said aperture adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move said cover into such an open position as to bear against said shell door if the same is open, and a breakable member so connected to said opening means as to restrain, while intact, said opening means from responding to the bias of said biased element or elements and, upon its rupture, to release said opening means for opening said movable cover under the action of said biased element or elements, and counterbalancing means connected to said shell door adapted to reduce the speed of the closing movement of said shell door below the speed at which this door, upon its closing movement having been initiated by said movable cover for said relief opening, would come down to its closing position under the unhampered action of its own weight.

13. In a dry-cleaning washer, in combination,

a shell, an opening in the front side of said shell, a shell door mounted on a hinge at the top of said opening and adapted to close the latter, a box attached to the outside of said shell behind said hinge and communicating with the interior of said shell through an aperture, a normally partly open closure for said aperture adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move said cover into such an open position as to bear against said shell door if the same is open, a breakable member so connected to said opening means as to restrain, while intact, said opening means from responding to the bias of said biased element or elements and, upon its rupture, to release said opening means for opening said movable cover under the action of said biased element or elements, and counterbalancing means for said shell door including a weight carried by a lever turnable about a pivot and extending from said pivot upwardly at an angle to the horizontal direction and a flexible member connecting the pivotal end of said lever to the hinged end of said shell door, so that said weight participates in the movement of said shell door and reduces the speed of the closing movement of said shell door below the speed at which this door, upon its closing movement having been initiated by said movable cover for said relief opening, would come down to its closing position under the unhampered action of its own weight.

14. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a normally partly open closure for said aperture adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move said cover into such an open position as to bear against said shell door if the same is open for initiating the closing thereof, a breakable member so connected to said opening means as to restrain, while intact, said opening means from responding to the bias of said biased element or elements and, upon its rupture, to release said opening means for opening said movable cover under the action of said biased element or elements, said normally partly open closure being pivotally mounted closely underneath said opening means for said cover so that in consequence of an explosion within said shell said closure will strike against said opening means, and counterbalancing means connected to said shell door adapted to reduce the speed of the closing movement of said shell door below the speed at which this door, upon its closing movement having been initiated by said movable cover for said relief opening, would come down to its closing position under the unhampered action of its own weight.

15. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a normally partly open closure for said aperture adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move said cover into such an open position as to bear against said shell door if the same is open for initiating the closing thereof, a breakable member so connected to said opening means as to restrain, while intact, said opening means from responding to the bias of said biased element or elements and, upon its rupture, to release said opening means for opening said movable cover under the action of said biased element or elements, said normally partly open closure being pivotally mounted closely underneath said opening means for said cover so that in consequence of an explosion within said shell said closure will strike against said opening means, and counterbalancing means for said shell door including a weight carried by a lever turnable about a pivot and extending from said pivot upwardly at an angle to the horizontal direction and a flexible member connecting the pivotal end of said lever to the hinged end of said shell door, so that said weight participates in the movement of said shell door, reducing the speed of the closing movement of said shell door below the speed at which this door, after its closing movement having been initiated by said movable cover for said relief opening, would come down to its closing position under the unhampered action of its own weight.

16. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a normally partly open closure for said aperture adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move said cover into such an open position as to bear against said shell door if the same is open, a fusible link so connected to said opening means as to restrain, while intact, said opening means from responding to the bias of said biased element or elements and, upon its rupture, to release said opening means for opening said movable cover under the action of said biased element or elements, said normally partly open closure being arranged so as to direct the blast of an explosion occurring in said shell towards said fusible link, and counterbalancing means connected to said shell door adapted to reduce the speed of the closing movement of said shell door

below the speed at which this door, upon its closing movement having been initiated by said movable cover for said relief opening, would come down to its closing position under the unhampered action of its own weight.

17. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a normally partly open closure for said aperture adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move said cover into such an open position as to bear against said shell door if the same is open, a fusible link so connected to said opening means as to restrain, while intact, said opening means from responding to the bias of said biased element or elements and, upon its rupture, to release said opening means for opening said movable cover under the action of said biased element or elements, said normally partly open closure being pivotally mounted closely underneath said opening means for said cover and in such position as to direct the blast of an explosion occurring in said shell towards said fusible link, and counterbalancing means for said shell door including a weight carried by a lever turnable about a pivot and extending from said pivot upwardly at an angle to the horizontal direction and a flexible member connecting the pivotal end of said lever to the hinged end of said shell door so that said weight participates in the movement of said shell door, reducing the speed of the closing movement of said shell door below the speed at which this door, upon its closing movement having been initiated by said movable cover for said relief opening, would come down to its closing position under the unhampered action of its own weight.

18. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a pivotally mounted closure for said aperture, a cam for normally holding said closure partly open, said closure being adapted to open further upon the occurrence of an explosion in said shell, an explosion relief opening in one of the walls of said box, a normally closed cover for said explosion relief opening, opening means interposed between said closure and said cover for opening the latter when said closure opens further due to an explosion in said shell, said opening means including at least one element biased for causing said opening means to move said cover into such an open position as to bear against said shell door if the same is open, and said cam to assume a position in which it is out of the path of said closure, a member adapted to break in consequence of an explosion within said shell so connected to said opening means as to restrain, while intact, said opening means from respond-

ing to the bias of said biased element or elements and, upon its rupture, to release said opening means for opening said movable cover and said cam for moving out of the path of said closure under the action of said biased element or elements, permitting thereby said closure to fall shut.

19. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a closure for said aperture in said box which is normally latched partly open and adapted to be opened further by the force of an explosion in said shell, an explosion relief opening in one of the walls of said box, a normally closed cover for said explosion relief opening, a normally closed system for supplying a fire extinguishing fluid to said shell including a valve, biased opening means for said cover and biased opening means for said valve, means including a breakable member for restraining said cover opening means and said valve opening means from becoming operative while said breakable member is intact, said breakable member being designed so as to be broken and thereby to release both said biased cover opening means and said biased valve opening means by a further opening of said closure due to an explosion in said shell.

20. In a dry-cleaning washer, in combination, a shell, an opening in the front side of said shell, a segment shaped shell door mounted on a shaft near the top edge of said opening and adapted to close the latter, said shaft projecting beyond one end of said shell door, a disk attached to said projecting end of said shaft, a pivot carried by said shell, a roller freely turnable about said pivot, a lever carried by said roller, a weight on said lever, a flexible band attached at one end to the rim of said roller and at its other end to the rim of said disk so that the torque of said weight about said pivot is opposed to the torque of said shell door about said shaft, thereby counter-balancing said shell door, an explosion outlet from said shell, a hinged cover on said outlet, spring-biased means tending to elevate said cover to strike against said shell door if the latter is open and thereby to provide the energy to impel said counter-balanced shell door to its closed position, a fire extinguishing fluid connection to said shell, a normally closed valve in said fluid connection, a second spring-biased means adapted to open said valve, a fusible link whose ends are connected to said two spring biased means respectively in such a manner that one spring biased means opposes the other spring biased means, so that upon rupture of said link said first spring-biased means will cause the shell door to be closed and the second spring-biased means will cause the shell to be flooded with fire extinguishing fluid.

21. In a dry-cleaning washer, in combination, a shell, an opening in the front side of said shell, a shell door mounted on a hinge at the top of said opening and adapted to close the latter, a box attached to the outside of said shell behind said hinge and communicating with the interior of said shell through an aperture, a pivotally mounted closure for said aperture, a cam for normally holding said closure partly open, said closure adapted to be opened further by the force of an explosion in said shell, an explosion relief

opening in one of the walls of said box, a normally closed cover for said explosion relief opening, a normally closed system for supplying a fire extinguishing fluid to said shell including a valve, biased opening means for said cover and biased opening means for said valve, restraining means including a breakable member for restraining said cover opening means and said valve opening means from becoming operative while said breakable member is intact while holding said cam in a position in which it prevents closing of said closure, said breakable member being so designed as to be broken and thereby to release both said biased opening means for said cover and said valve by a further opening of said closure due to an explosion in said shell and also to release said cam for moving out of the path of said closure, permitting thereby said closure to fall shut, confining thereby the fluid supplied to said shell by said valve to the interior of said shell.

22. A dry-cleaning washer which will instantaneously vent an explosion therein and smother the subsequent blaze without blowing the loading door open against the operator, having in combination, a shell, an opening in the front side of said shell for the loading door, a shell door mounted on a hinge at the top of said opening and adapted to be closed during the operation of the washer, a box attached to the outside of said shell behind said hinge and communicating with the interior of said shell through an aperture therein, a closure for said aperture in said box which is normally latched partly open and adapted to be opened further by the force of the explosion within said shell and unlatched to close said aperture, an opening in one wall of said box to the atmosphere, a normally closed cover for said opening, a device providing the energy for moving said cover to a position where the opening from the box to the atmosphere is unobstructed, means normally restraining said device from acting which are adapted to be ruptured by the movement of the closure of said aperture beyond its initial partly-open position.

23. In a dry-cleaning washer fire extinguishing means, including in combination, a shell, an opening in the front side of said shell, a shell door mounted on a hinge at the top of said opening and adapted to close said opening, a box attached to the outside of said shell behind said hinge and in communication with the interior of said shell through an aperture in the shell, a pressure relief opening to the ambient atmosphere in one of the walls of said box, a normally closed cover for said pressure relief opening, a system adapted to supply fire extinguishing fluid to said shell, a normally closed valve in said system, a first spring tending to open said cover, a second spring tending to open said valve, a connection between said two springs including a frangible member which restrains both springs, a pivotally mounted closure for said aperture adapted to break said frangible member when forcibly swung open by an explosion in the shell, a cam normally in a position to hold said closure partly open but moved out of contact with said closure when the cover is open thereby allowing the closure to fall shut after the frangible member is broken, and the second spring has initiated the flow of fire extinguishing fluid through said valve and the first spring has opened the cover to allow the escape of the pressure created by the explosion.
